CLAIM

The ornamental design for a chaise lounge cover, as shown and described.

DESCRIPTION

FIG. 1 is a front, left side, top perspective view of a chaise lounge cover showing my new design;

FIG. 2 is a front, right side, bottom perspective view thereof;

FIG. 3 is a left side elevational view thereof;

FIG. 4 is a right side elevational view thereof;

FIG. 5 is a rear elevational view thereof;

FIG. 6 is a front elevational view thereof;

FIG. 7 is a top plan view thereof;

FIG. 8 is a bottom plan view thereof;

FIG. 9 is a front, left side, top perspective view thereof when being used to cover a chaise lounge; and,

FIG. 10 is a front, right side, bottom perspective view thereof when being used to cover a chaise lounge.

The broken lines depict environment that forms no part of the claimed design for the chaise lounge cover.

1 Claim, 10 Drawing Sheets
